REFRIGERATION SYSTEM CONDENSER ARRANGEMENT

Lester K. Quack, 600 Howard St., Eugene, Oreg. 97402
Filed Aug. 24, 1965, Ser. No. 482,142
16 Claims. (Cl. 62—196)

ABSTRACT OF THE DISCLOSURE

A condenser arrangement for a closed cycle refrigeration system for reclaiming heat to accomplish space heating and for maintaining head pressure under varying conditions wherein a heat-reclaiming condenser is selectively placed in series between the compressor discharge and a full capacity heat-rejecting condenser of the system for heating and such heat-rejecting system condenser has plural coils in parallel with valving for successively connecting and disconnecting such coils for varying the condensing capacity to maintain head pressure, with one such coil always remaining in the system and adapted to be flooded to maintain head pressure even under extreme conditions.

This invention relates to a refrigeration system and in particular is directed to improvements in the condenser arrangement of a refrigeration system employing a multiplicity of separate evaporators operated by a central compressor means such as for a modern supermarket installation.

In many supermarket installations employing a central compressor system the heat load produced by the refrigerated fixture evaporators is used to heat the interior of the building during appropriate seasons by circulating air past the refrigeration system condenser and discharging the heated air into the supermarket. However, at other times of the year when space heating is not desired, the heat extracted from the condenser must be dissipated to the atmosphere. While arrangements have been developed for modulating the air flow from the atmosphere or store, past the condenser and then to the store or atmosphere as required, these arrangements have been found to be expensive and somewhat difficult to obtain the proper control. Other arrangements employing separate interior and exterior air cooled condensers and diverting or modulating refrigerant flow therebetween requires that both condensers be of a sufficient capacity for condensing the full refrigerant load resulting in excessive costs and an unnecessary duplicity of components. Moreover, the valving and piping of such arrangements become extremely complex and costly, as well as difficult to properly size and install particularly in situations where the interior or space heating condenser is remotely located from the compressor and exterior condenser. These difficulties are greatly magnified when it is desired to heat separate zones or buildings by reclaiming the heat developed by the refrigeration system.

Another difficulty which is encountered with a refrigeration system of this type is controlling the head pressure within the desired or optimum range in spite of the vast fluctuation in the demands of the system and in the ambient conditions. This is particularly true when an air cooled condenser is used for dissipating the unwanted heat of the system and yet the general desirability of using air cooled type condensers is well-known to the industry. The vast difference in climatic conditions encountered in various parts of the country has resulted in the necessity

2

of specially designing and engineering the heretofore conventional condenser arrangements to match the climatic conditions which has prevented standardization of the arrangements. While there are well-known control arrangements for maintaining the desired head pressure in the refrigerant system regardless of the ambient conditions to which the condenser is subjected, such arrangements require a nearly complete flooding or filling of the condenser with the resultant requirement that an excessive amount of refrigerant must be provided in the system to permit this flooding under these periodically occurring adverse conditions. Moreover, the possible beneficial effect of any sub-cooling which could be derived from condenser flooding is usually lost by reason of past methods of controlling the head pressure, which required the introduction of hot gaseous refrigerant to the outlet of the condenser thereby heating the sub-cooled refrigerant.

Accordingly, it is a principal object of this invention to provide a novel condenser arrangement for a refrigeration system wherein the heat may be reclaimed or dissipated to ambient as desired and is capable of operating under all ranges of ambient conditions while maintaining the desired head, final or last condenser and liquid line pressures.

Another object of this invention is to provide a novel condenser arrangement for selectively reclaiming the heat developed in a refrigeration system wherein interior and exterior condensers are connected in series to permit the reclamation of any desired quantity of heat and the automatic dissipation to ambient of the balance of the heat by the exterior condenser.

A further object of this invention is to provide a novel form of condenser arrangement wherein multiple separate condenser coils are connected in series flow relationship for heat reclamation and in a final stage parallel flow relationship for disconnecting each separate condenser coil as required to adjust the capacity of the complete condenser thereby maintaining the desired liquid line pressures in the system.

A still further object is to provide such a multiple coil condenser arrangement in the final stage wherein at least the first of such coils to be closed off is used to sub-cool the liquid refrigerant produced by the remaining condenser coils. Still another object of this invention is to provide such a multiple coil condenser arrangement wherein the maximum extent of flooding which will occur is the capacity of the last of the condenser coils left connected in the system thereby reducing the quantity of refrigerant used in flooding to a mere fraction of that normally required by a condenser of the same total capacity.

A further object of this invention is to provide a novel refrigeration heat reclaiming condenser which may be incorporated in a multizone heating and air conditioning system without the necessity of dissipating any heat from that heat reclaiming condenser.

A further object of this invention is to provide a novel arrangement in a refrigeration system for controlling both the head pressure and the liquid line pressure regardless of ambient or load conditions whereby optimum operation is achieved.

Other and more detailed objects and advantages of this invention will be apparent from the following description and the accompanying drawing which is a diagrammatic illustration of the preferred embodiment of this invention.

For convenience, the system of this invention has been

illustrated and will be described as the type of system which might be included in a supermarket although it is to be understood and will readily appear to those skilled in the art that the system can be readily adapted to other installations. The roof 10 of the supermarket is schematically shown to illustrate the separation between the exterior atmosphere 11 and the interior space 12 which requires heating or air conditioning.

With reference to the refrigeration system itself, a surge-type refrigerant receiver 13 is connected through a large base conduit 14 forming a gas-separating chamber having a T-connection with a liquid refrigerant conduit 15 between a condenser assembly and a conventional sub-cooler 16 to a liquid header 17. The header 17 serves to conduct liquid refrigerant to each of the branch conduits leading to an evaporator coil associated with a refrigerated fixture. Three evaporator coils 18, 19 and 20 are shown for illustration purposes but it will readily appear to those skilled in the art that numerous other evaporator coils will normally be connected in the same manner. Evaporators are provided with conventional control means such as expansion valves 21 and under normal refrigerating operations are connected through the three-way valves 22 to a suction header 23 returning the evaporated refrigerant to the intake of the refrigeration system compressor 25. The aforementioned sub-cooler 16 is operated only when adequate sub-cooling is not accomplished by the hereinafter described condenser arrangement and then only to the degree necessary to prevent flash gas from occurring in the liquid header 17. The sub-cooler 16 may be of the type employing an evaporator coil surrounding a conduit connection between liquid line 15 and liquid header 17 with such coil being provided with an expansion valve 26 and the outlet of the coil being provided with a back-pressure modulating valve 27 which is responsive to the temperature of the refrigerant leaving the sub-cooler and entering header 17. From modulating valve 27 the outlet of the sub-cooler is connected through line 28 to the suction header 23.

Although it is not essential to this invention, it has become somewhat conventional in these refrigeration system installations to utilize the so-called hot gas defrosting technique for the evaporator coils and this is shown in the drawing by the defrost gas header 29 which is connected from the upper portion of the receiver 13 to the three-way outlet valves 22 of the evaporators. Evaporator coil 20 is illustrated as being defrosted in this manner with the valve 22 connecting the defrost gas header 29 to the coil to pass refrigerant gas from the upper portion of the receiver through the coil and thence through a by-pass conduit 30 into the liquid header 17. A check valve 31 is provided in the by-pass header 30 to prevent reverse flow therethrough under normal refrigerating conditions which would abort the operation of the expansion valve 21. In order to provide an incentive for the flow of defrosting refrigerant from the evaporator coil into the liquid header 17, a normally open solenoid valve 32 is provided in liquid header 17 and is operated to a closed position during the defrosting of any of the evaporators of the system. A by-pass conduit having a pressure regulator valve 33 is connected to liquid header 17 on either side of solenoid valve 32. Pressure regulating valve 33 establishes a pressure differential thereacross to create a sufficiently low pressure in liquid line 17 to accept the defrosting refrigerant and, for example, a pressure drop of 20 p.s.i. across regulator valve 33 has been found satisfactory. The system as thus far described forms no part of the subject invention but is described as one example of the entire operable refrigeration system.

The condenser arrangement of this invention is illustrated and will now be described as operating under intermediate climatic conditions when space heating may be required in certain areas and not required in other areas and when the ambient atmospheric conditions are such as not to cause either excessively high or low outside

condenser pressures. "Inside" or "interior" condenser is used herein to designate condenser coils utilized for heat reclaiming purposes and "outside" or "exterior" condenser is used to designate final stage condensing although such condenser coils may be positioned in any housing structure designed to dissipate the heat of rejection to ambient. The variations of the positions and operation of the various control means for the condenser arrangement of the present invention under more severe climatic conditions will be described hereinafter as appropriate. The discharge 10 35 of the compressor 25 is connected through a four-way valve 36 to a discharge header 37. The discharge header 37 is connected to any desired number of branch conduits 38 leading to interior condensers employed for heating the interior 12 of the building by reclaiming the heat removed by the operation of the evaporators 18, 19 and 20 of the system. Two interior condenser coils 39 and 40 are illustrated in the drawing as connected in parallel to branch conduits 38 leading from discharge header 37, but it is to be understood that any number of condenser 20 25 coils may be connected to this parallel relationship as is required to accomplish the heating in the various spaced or remote zones or areas of that building or even buildings in the near vicinity. For example, in the illustrated system the condenser coil 39 may be associated with the office space of the building while the condenser coil 40 may be associated with the main heating and air conditioning unit, generally designated 41, for properly ventilating and controlling the temperature of the public portion of 25 30 the supermarket. The unit 41 includes air circulation means as described hereinafter, and the condenser 39 has air circulation means 39'. Separate three-way valves 42 and 43 are connected between the branch conduits 38 and the condenser coils 39 and 40, respectively, and the 35 valves 42 and 43 are separately controlled by thermostats 44 and 45, respectively associated with the particular spaces requiring heat so that hot gaseous refrigerant is selectively diverted through the condensers 39 and 40 in response to a heat demand actuation of the valves 42 and 40 45 50 55 60 65 70 75 43 by the thermostats. As illustrated in the drawings, the thermostat 44 reflects that the space does not require heating thereby closing the valve 42 to isolate the condenser coil 39 from the branch conduit 38. In contrast, thermostat 45 reflects the need for heat whereby valve 43 is open between branch conduit 38 and condenser coil 40 to pass the entire hot gas discharge from the compressor 25 through condenser 40 to reclaim the maximum available heat if so desired. The outlets of the condenser coils 39 and 40 are connected through pressure regulating valves 46 and 47, respectively and check valves 48 and 49, respectively, to a header 50 leading to the exterior condenser assembly, generally designated 51. The check valves 48 and 49 prevent the flow of refrigerant in a reverse direction into the condenser coils 39 and 40 as might occur under certain conditions such as when the three-way inlet valves 42 or 43 are closed to branch conduits 38 and the entire refrigerant discharge of the compressor is diverted or by-passed to the condenser assembly 51 to thereby enable the condensers 39 and 40 to be connected to a refrigerant pump down circuit 52. The three-way valves 42 and 43 are connected to the pump down conduit 52 which is in turn connected to the suction header 23 whereby any condensed refrigerant present in the condenser coil 39 or 40 at the time either valve 42 or 43 is closed from branch conduits 38 will be evaporated and drawn back into the system by compressor 25 thereby reducing the quantity of refrigerant charge required in the system by eliminating this useless accumulation of liquid refrigerant in these shut-down condenser coils 39 or 40.

The pressure regulating valves 46 and 47 are of the type which maintain a constant upstream pressure thereby maintaining a preselected minimum refrigerant pressure in the condenser coils 39 and 40 during their operation 75 and, obviously, this will be the minimum head pressure

of the compressor 25. The pressure setting of valves 46 and 47 will always be above the minimum desired liquid refrigerant line pressure of the refrigeration system as the receiver 13 and liquid lines 15 and 17; for example, with refrigerant 22 an optimum liquid line pressure may be in the realm of 150 p.s.i. However, it will be understood that the pressure setting of the valves 46 and 47 does not establish the liquid line pressure and that the head pressure must be high enough to force refrigerant condensed in the condensers 39 and 40 to the condenser assembly 51. The exact setting of valves 46 and 47 will depend on the most economical condition that may be achieved in that particular geographical location in which the system is installed, due to the relative cost of the electrical power for operating the compressor 25 and of the fuel which may be used to supplement the heating derived from condenser coils 39 and 40. The higher the pressure setting of valves 46 and 47, the higher will be the head pressure thereby increasing the power consumption of compressor 25 but proportionally increasing the heat which may be reclaimed by condensers 39 and 40. However, if fuel costs are extremely low then the lowest practical head pressure will produce the most economical operation and therefore valves 46 and 47 may be set to maintain a constant pressure at or slightly above the minimum desired liquid line pressure of approximately 150 p.s.i.

Another pressure regulating valve 53 is provided in the branch conduit 54 connected between header 50 leading to outside condenser assembly 51 and the discharge conduit 35 from the compressor 25. Pressure regulating valve 53 is adjusted to a pressure setting slightly in excess of the setting of regulating valves 46 and 47 whereby the head pressure on compressor 25 will not exceed the setting of valve 53. Thus, for example, as the system is illustrated with condenser coil 39 shut off, the capacity of condenser coil 40 may not be sufficient to handle the full output of compressor 25 without unduly increasing the head pressure whereby the head pressure will tend to exceed the value setting of valve 47. The valve 53 will open when the head pressure reaches its value setting to pass some of the hot gaseous refrigerant directly to the outside condenser assembly 51 thereby providing adequate condenser capacity and maintaining the head pressure of the compressor 25 between the settings of the valves 46, 47 and the valve 53.

When all of the interior heat-reclaiming condenser coils are shut down, such as during the warm summer months, then four-way valve 36 is shifted to a position for connecting discharge line 35 directly to header 50 rather than header 37 and this may be accomplished by an appropriate electrical circuit responsive to the thermostats 44 and 45. It will be understood that each thermostat 44 or 45 is independently responsive to demands for space heating for actuating its valve 42 or 43 to connect the respective condenser 39 or 40 to the header 37, and that the main refrigerant distributing valve 36 must also be actuated by each thermostat 44 or 45 to connect the discharge line 35 to the header 37. Obversely, the valve 36 must be actuated to connect the discharge line 35 to the header 50 only when all of the interior condensers are in a non-heating condition. When the four-way valve 36 connects the conduit 35 to the header 50, the header 37 is connected to a pump down conduit 55 and a normally closed solenoid valve 56 is opened to connect the header 37 to the intake of the compressor 25 thereby evaporating and removing the liquid refrigerant which might otherwise accumulate in header 37 and branch conduits 38. Again, this evacuation or pump down minimizes the quantity of refrigerant that might otherwise be required in the entire system to accommodate these various conditions of operation and also serves to prevent damage which might occur from forcing a quantity of accumulated refrigerant through header 37 and the condenser coils upon returning the four-way valve 36 to the position shown in the drawing. It is to be understood that solenoid valve 56 is closed

when four-way valve 36 connects the discharge 35 to header 37.

The outside condenser assembly 51 serves to condense the entire discharge of the compressor 25 when four-way valve 36 connects such discharge directly to header 50 or to condense any portion of the refrigerant which passes through the heat-reclaiming condenser coils 39 and 40 without being condensed. Thus, the capacity of outside condenser assembly 51 must be sufficient to handle the complete compressor discharge under the warmest expected ambient conditions and yet must not rob the entire refrigeration system of the refrigerant charge by completely flooding during severely cold ambient conditions when perhaps the entire refrigerant discharge of compressor 25 is condensed by the heat reclaiming condenser coils 39 and 40. To this end the outside condenser assembly 51 is provided with a plurality of separate condenser coils, three of which are shown and designated 60, 61 and 62, connected in parallel relationship between the header 50 and a liquid refrigerant line 63. The ambient air is circulated past the condenser coils 60, 61 and 62 by any convenient means such as a fan 64 and such air circulation may be in either series or parallel relation through said condenser coils. Three condenser coils are shown but it will readily appear to those skilled in the art that any number of parallel connected coils may be employed and additional coils would normally be connected and controlled in a manner similar to coil 61 or perhaps coil 62 as hereinafter described. All but one of the condenser coils are connected to header 50 by means of a three-way valve which is pressure controlled. As shown in the drawing, coil 60 is connected directly to header 50 and three-way valves 65 and 66 are provided between header 50 and condenser coils 61 and 62, respectively. A pressure control 67 responsive to the outside condenser pressure in header 50 operates the three-way valves 65 and 66 to successively close the three-way valves as the pressure drops below the minimum desired level which again depends on the desired minimum liquid line pressure. For example, as the pressure drops in header 50 below the pre-selected value as might occur when part of the condensing is being accomplished by the interior condenser coils 39 and 40 or under low ambient conditions, the control 67 shifts valve 66 to the position shown in the drawing thereby disconnecting coil 62 from header 50 and increasing the condensing load upon the remaining condenser coils 60 and 61, thereby causing the outside condenser pressure to rise to the desired level. If the ambient temperature continues to drop and the combined capacity of condenser coils 60 and 61 is excessive whereby the pressure in header 50 drops below the desired level then control 67 shifts valve 65 to disconnect coil 61 from header 50 thereby reducing the capacity of outside condenser assembly 51 to the single coil 60. The outlet of condenser coil 60 is controlled by a pressure regulating valve 68 for maintaining a minimum pressure on condenser coil 60. Pressure regulating or throttling valve 68 is set to a value which will cause partial flooding of condenser coil 60 as the outside condenser pressure in header 50 begins to drop and before the valves 65 and 66 are shifted to disconnect condenser coils 61 and 62, thereby partially reducing the effective condensing area of coil 60 thereby automatically adjusting the overall capacity of the outside condenser assembly 51. As the pressure continues to drop and condenser coil 60 becomes nearly flooded then the pressure control 67 functions in the aforescribed manner to first shift valve 66 to disconnect coil 62 to further decrease condenser capacity and increase pressure to reduce or eliminate the flooding of coil 60 until the pressure again begins to drop.

Under intermediate conditions between the shifting of the valves 65 and 66 the condenser coil 60 may be partially flooded thereby sub-cooling the liquid refrigerant leaving the coil and passing through the pressure regulating or throttling valve 68 to the liquid line 63. Sub-

cooling of the liquid refrigerant is of well-known advantage and can result in substantial power savings if such sub-cooling is obtained without additional expenditure of power as is involved in the use of sub-cooler 16.

At least one of the separate parallel condenser coils of the outside condenser assembly 51 may be connected to accomplish sub-cooling of the condensed refrigerant and, as shown in the drawing, such coil should be the first coil to be disconnected from the hot gas header by means of the pressure control 67. Condenser coil 62 is so connected whereby the shifting of three-way valve 66 connects the coil to a conduit 71 which is in turn connected to the liquid line 63 downstream of a solenoid valve 72. When valve 66 is shifted by control 67 to connect the coil 62 to conduit 71 the control 67 also serves to close solenoid valve 72 thereby causing the condensed refrigerant received from coils 60 and 61 to pass through coil 62 in a reverse direction and effect sub-cooling of such refrigerant. By this arrangement of outside condenser assembly 51 the proper liquid line pressure is continually maintained (rather than requiring the inefficient introduction of hot gaseous refrigerant to the outlet of the condenser as in the past) and advantageous sub-cooling is automatically and efficiently obtained under all but the hottest ambient conditions.

Condenser coil 61 is connected to line 63 through a check valve 69 to prevent reverse flow through the condenser coil when the valve 65 is shifted to disconnect the coil from header 50. In shifting valve 65 to disconnect condenser coil 61 from the header the valve connects the coil to a pump down line 70 connected to the intake of compressor 25 whereby any liquid refrigerant accumulated within condenser coil 61 will be evaporated and returned to the system, again minimizing the quantity of refrigerant charge that might otherwise be required in this system. If the sub-cooling arrangement of the condenser 62 is not needed or desired, the condenser 62 may be connected to a pump down conduit similar to that of the condenser 61.

Liquid line 63 is connected to liquid line 15 passing below and in communication with the surge-type receiver 13 to normally pass sub-cooled liquid refrigerant to the header 17 and also into the receiver 13. An important feature of this invention is the maintenance of a liquid line pressure above a predetermined minimum level. In the refrigeration system disclosed, the evaporators 18, 19 and 20 are defrosted by substantially saturated gas taken from the top of the receiver 13 through header 23. Therefore, to maintain a constant supply to saturated gas in the receiver 13 and prevent condensation thereof due to the sub-cooled refrigerant delivered to the liquid line 15 (and while maintaining the liquid line pressure throughout the receiver), a temperature stratification of liquid refrigerant in the receiver 13 is provided in which the upper strata or layer of refrigerant is at the same temperature as the saturated gas and isolates the sub-cooled liquid from such saturated gas to prevent condensation thereof. Conduit 75 is connected between the compressor discharge 35 and the top of the receiver 13, and a pressure regulating valve 79 is provided in conduit 75 and constitutes a minimum pressure control for maintaining a minimum pressure on the downstream side of the valve thereby maintaining a predetermined minimum pressure in the receiver 13 which pressure is adjusted to the desired liquid line pressure of the system. If for any reason the pressure in receiver 13 drops below the pressure setting of valve 79 as might occur during defrosting of one or more of the evaporators when valve 68 is throttled down or closes to maintain head pressure or when sub-cooled liquid refrigerant is drawn into the receiver 13 under conditions creating a high degree of turbulence intermixing the warm insulating refrigerant strata therewith, then the valve 79 opens to maintain the minimum receiver pressure and maintain the relatively warmer upper strata of liquid refrigerant in the receiver 13.

receiver 13. An equalizing line 80 having a check valve 81 is connected between the receiver 13 and the condenser header 50 for equalizing the pressure therebetween if the outside condenser pressure in header 50 drops below pressure in receiver 13. By this entire arrangement the condensed refrigerant which may be sub-cooled in the aforescribed manner by the outside condenser assembly 51 will pass through line 15 and by the gas separating chamber 14 and receiver 13 without mixing such sub-cooled liquid refrigerant with the refrigerant in receiver 13 which may be at a much higher temperature. Of course, if the liquid refrigerant passing from line 15 to liquid header 17 is sub-cooled then the conventional sub-cooler 16 is no longer operated. Due to fluctuations in liquid refrigerant requirements by the evaporators the level in receiver 13 may vary, but by this arrangement the cold refrigerant will always be introduced at the bottom of the receiver and be withdrawn from the bottom of the receiver tending to produce stratification of the liquid refrigerant into levels commensurate with its temperature.

By the aforescribed condenser arrangement it may be seen that any desired minimum quantity of heat may be reclaimed without adversely affecting head pressures or requiring full capacity, interior condenser coils. Further, in accordance with the objects of the invention, the interior and exterior condensers cooperate to provide complete liquid line and head pressure control in a precise and economical manner. One or more heat-reclaiming condenser coils of this arrangement may be associated with a conventional multizone heating and air conditioning unit 41 even though such unit does not dissipate the entire heat available or provide the entire condensing requirements of the system and even though different or additional heat reclaiming condensers, such as coil 39, may be provided, as disclosed. As shown, a separate air conditioning system, generally designated 90, has an evaporator coil 91 positioned in the cooling section of the multizone unit 14. As is conventional, the air conditioning system comprises a compressor 92, a condenser 93 and receiver 94 for supplying refrigerant to the evaporator coil 91. Further, as is conventional with a multizone type unit, a ventilating fan 95 passes air over the heating coil (which is the refrigeration condensing coil 40 in the present system) and cooling coil 91 in relative quantities as controlled by the cooperable modulating dampers 96 and 97, respectively, which are shown in a position for accomplishing full heating. Shifting of the dampers 96 and 97 to an intermediate position or even a full cooling position does not adversely affect the operation of the main refrigeration system since the hot compressed refrigerant will pass through condenser coil 40 without condensing due to the closed damper 96 and lack of air circulation across the condenser and the uncondensed refrigerant will eventually be condensed by the outside condenser assembly 51.

Having fully described my invention, it is to be understood that I do not wish to be limited to the details herein described or shown in the drawing but my invention is of the full scope of the appended claims.

I claim:

1. A condenser arrangement for a closed cycle refrigeration system of the type having a compressor, condenser and evaporator, comprising, first condenser means associated with a space to be heated, second condenser means adapted for dissipating heat from the system, conduit means connecting said first and second condenser means in series and between the compressor and the evaporator, said second condenser means being of a sufficient capacity to condense the entire gaseous refrigerant output of the compressor, said second condenser means having plural condenser coils normally connected in parallel relationship, and valve means for successively disconnecting all but one of said condenser coils from the compressor in response to declining compressor head pressure for suc-

cessively reducing the condensing capacity and maintaining a desired minimum compressor head pressure.

2. A condenser arrangement for a closed cycle refrigeration system, comprising, a receiver means for liquid refrigerant, evaporator means connected to said receiver means and producing a refrigerant heat load, compressor means for compressing the evaporated refrigerant, first condenser means associated with a space to be heated, second condenser means exposed to atmospheric conditions for dissipating heat, conduit means connecting said first condenser means in series between said compressor means and said second condenser for making the full heat load available to said first condenser means for heating the space, said second condenser means being of a sufficient capacity to condense the entire gaseous refrigerant output of the compressor means when no heating of the space by said first condenser means is required, said second condenser means having plural condenser coils normally connected in parallel relationship to said receiver means, and valve means for successively disconnecting all but one of said condenser coils of said second condenser means from said compressor means for reducing the condensing capacity and maintaining compressor head pressure.

3. A condenser arrangement for a closed cycle refrigeration system of the type employing a compressor, condenser and evaporator means, comprising, a plurality of condenser coils connected in parallel relationship and exposed to fluctuating conditions for dissipating heat, conduit means connecting said parallel condenser coils between the compressor and evaporator means, said condenser coils being of a sufficient aggregate capacity to condense the entire gaseous refrigerant output of the compressor, valve means for successively disconnecting all but one of said condenser coils to adjust the condenser capacity to a level commensurate with the heat being dissipated, and valve and conduit means for reconnecting at least one of said disconnected condenser coils in series with and downstream of the remaining condenser coils operatively connected to the compressor for passing refrigerant through said reconnected coil for sub-cooling the condensed refrigerant.

4. A condenser arrangement for a closed cycle refrigeration system of the type employing a compressor, condenser and evaporator means, comprising, a plurality of condenser coils connected in parallel relationship and exposed to fluctuating conditions for dissipating heat, conduit means connecting said parallel condenser coils between the compressor and evaporator means, said condenser coils being of a sufficient aggregate capacity to condense the entire gaseous refrigerant output of the compressor, valve means for successively disconnecting all but one of said condenser coils to adjust the condenser capacity to a level commensurate with the heat being dissipated, for reconnecting at least one of said disconnected condenser coils in series with and downstream of the remaining condenser coils connected to the compressor for sub-cooling the condenser refrigerant in said disconnected coil, and pressure regulating valve means on the outlet of the said one condenser coil which remains connected to the compressor for maintaining a preselected pressure in that coil by flooding that coil as required.

5. A condenser arrangement for a refrigeration system, comprising, a receiver means for liquid refrigerant, evaporator means connected to said receiver means and producing a refrigerant heat load, compressor means for compressing the evaporated refrigerant, first condenser means associated with a space to be heated, pressure regulating valve means associated with said first condenser means for selectively controlling the pressure in said first condenser means, second condenser means exposed to ambient atmospheric conditions for dissipating heat, conduit means connecting said first condenser means in series between said compressor means and said second condenser for making the full heat load

available to said first condenser means for heating the space, said second condenser means comprised of a plurality of condenser coils normally connected in parallel relationship to said receiver means, and valve means for successively disconnecting all but one of said condenser coils of said second condenser means from said compressor means when not required to accomplish the complete condensing.

6. A condenser arrangement for a refrigeration system arranged for selectively reclaiming heat to heat an enclosed space, comprising, a receiver means for liquid refrigerant, evaporator means connected to said receiver means and producing a refrigerant heat load, compressor means for compressing the evaporated refrigerant, first condenser means associated with the space to be heated, said first condenser means including a plurality of separate condenser coils connected in parallel, thermostatically controlled valve means operatively connected to each said separate condenser coil for selectively passing gaseous refrigerant through the associated condenser coil as required for space heating, second condenser means associated with ambient atmospheric conditions for dissipating heat, conduit means connecting said first condenser means in series between said compressor means and said second condenser for making the full heat load available to said first condenser means for heating the space, and pressure regulating valve means connecting said compressor means to said second condenser means for by-passing said first condenser means to prevent exceeding a maximum head pressure on said compressor means, said second condenser means being of a sufficient capacity to condense the entire gaseous refrigerant output of the compressor means when no heating of the space by said first condenser means is required.

7. A condenser arrangement for a closed cycle refrigeration system comprising, a receiver means for liquid refrigerant, evaporator means connected to said receiver means and producing a refrigerant heat load, compressor means for compressing the evaporated refrigerant, first condenser means associated with a space to be heated, said first condenser means including a plurality of separate condenser coils connected in parallel, thermostatically controlled valve means operatively connected to each said separate condenser coil for selectively passing gaseous refrigerant through the associated condenser coil as required for space heating, second condenser means exposed to ambient atmospheric conditions for dissipating heat, conduit means connecting said first condenser means in series between said compressor means and said second condenser for making the full heat load available to said first condenser means for heating the space, said second condenser means being of a sufficient capacity to condense the entire gaseous refrigerant output of the compressor means when no heating of the space by said first condenser means is required, and pressure regulating valve means associated with said first condenser means for maintaining a predetermined pressure in said first condenser means during operation thereof.

8. A condenser arrangement for a closed cycle refrigeration system, comprising, a receiver means for liquid refrigerant, evaporator means connected to said receiver means and producing a refrigerant heat load, compressor means for compressing the evaporated refrigerant, first condenser means associated with a space to be heated, second condenser means exposed to ambient atmospheric conditions for dissipating heat, means for selectively connecting said first condenser means in series between said compressor means and said second condenser as space heating is required, and said second condenser means being of a sufficient capacity to condense the entire gaseous refrigerant output of the compressor means when no heating of the space by said

first condenser means is required, said second condenser continuously connected in condensing relation in the refrigeration system and having the outlet connected to said receiver.

9. A condenser arrangement for a closed cycle refrigeration system, comprising, a receiver means for liquid refrigerant, evaporator means connected to said receiver means and producing a refrigerant heat load, compressor means for compressing the evaporated refrigerant, first condenser means associated with a space to be heated, second condenser means exposed to ambient atmospheric conditions for dissipating heat, means for selectively connecting said first condenser means in series between said compressor means and said second condenser, said second condenser means being of a sufficient capacity to condense the entire gaseous refrigerant output of the compressor means when no heating of the space by said first condenser means is required, and pressure regulating valve means on the outlet of said first condenser means for maintaining a predetermined pressure in said first condenser means during operation thereof.

10. A condenser arrangement for a closed cycle refrigeration system, comprising, a receiver means for liquid refrigerant, evaporator means connected to said receiver means and producing a refrigerant heat load, compressor means for compressing the evaporated refrigerant, first condenser means associated with a space to be heated, second condenser means exposed to ambient atmospheric conditions for dissipating heat, conduit means connecting said first condenser means in series between said compressor means and said second condenser, said second condenser means being of a sufficient capacity to condense the entire gaseous refrigerant output of the compressor means when no heating of the space by said first condenser means is required, and means including a pressure regulating valve means connecting said compressor means to said receiver means for maintaining a predetermined minimum pressure in said receiver means for supplying liquid refrigerant to said evaporator means.

11. A condenser arrangement for a closed cycle refrigeration system comprising, a receiver means for liquid refrigerant, evaporator means connected to said receiver means and producing a refrigerant heat load, compressor means for compressing the evaporated refrigerant, first condenser means associated with a space to be heated, pressure regulating valve means associated with said first condenser means for selectively controlling the pressure in said first condenser means, second condenser means exposed to ambient atmospheric conditions for dissipating heat, conduit means connecting said first condenser means in series between said compressor means and said second condenser for making the full heat load available to said first condenser means for heating the space, pressure regulating valve means connecting said compressor means to said second condenser means for by-passing said first condenser means to prevent exceeding a maximum head pressure on said compressor means, said second condenser means being of a sufficient capacity to condense the entire gaseous refrigerant output of the compressor means when no heating of the space by said first condenser means is required, and means including a pressure regulating valve means connecting said compressor means to said receiver means for maintaining a predetermined minimum pressure in said receiver means for supplying liquid refrigerant to said evaporator means.

12. A condenser arrangement for a closed cycle refrigeration system comprising, a receiver means for liquid refrigerant, evaporator means connected to said receiver means and producing a refrigerant heat load, compressor means for compressing the evaporated refrigerant, first condenser means associated with a space to be heated, pressure regulating valve means associated with said

first condenser means for selectively controlling the pressure in said first condenser means, said first condenser means including a plurality of separate condenser coils connected in parallel, thermostatically controlled valve means operatively connected to each said separate condenser coil for selectively passing gaseous refrigerant through the associated condenser coil as required for space heating, second condenser means exposed to ambient atmospheric conditions for dissipating heat, conduit means connecting said first condenser means in series between said compressor means and said second condenser for making the full heat load available to said first condenser means for heating the space, pressure regulating valve means connecting said compressor means to said second condenser means for by-passing said first condenser means to prevent exceeding a maximum head pressure on said compressor means, said second condenser means being of a sufficient capacity to condense the entire gaseous refrigerant output of the compressor means when no heating of the space by said first condenser means is required, said second condenser means having plural condenser coils normally connected in parallel relationship to said receiver means, valve means for successively disconnecting all but one of said condenser coils of said second condenser means from said compressor means for reducing the condensing capacity and maintaining a preselected head pressure, and pressure regulating valve means on the outlet of the said one condenser coil which remains connected to the compressor for maintaining a preselected pressure in that coil by flooding that coil as required.

13. In a refrigeration system requiring a predetermined maximum condensing capacity, first condenser means having said predetermined maximum condensing capacity and continuously connected in condensing relation in the refrigeration system, second condenser means having a condensing capacity less than said predetermined maximum condensing capacity of said first condenser means, and means responsive to predetermined conditions for connecting said first and second condenser means in series refrigerant flow relationship with the outlet of said second condenser means connected to the inlet of said first condenser means.

14. In a refrigeration system having compressor means, receiver means, evaporator means and a liquid header connecting said evaporator means to the bottom of said receiver means; condenser means between said compressor and receiver means for condensing hot gaseous refrigerant from said compressor means, means for operating said condenser means in at least a partially flooded condition for sub-cooling condensed liquid refrigerant, means connecting said condenser means to said liquid header at the bottom of said receiver means for conducting sub-cooled refrigerant to said liquid header and producing temperature stratification of liquid refrigerant in said receiver means with the coldest refrigerant zone being at the bottom of said receiver means, and other means adapted to connect said compressor means with the top of said receiver means for maintaining a predetermined minimum pressure in said receiver means and liquid header and for maintaining said temperature stratification of liquid refrigerant in said receiver means.

15. A condenser arrangement for selective reclamation of heat from a closed cycle refrigeration system, comprising a first condenser positioned to give up heat to the space to be heated, a second condenser positioned to reject and dissipate heat from the system, said second condenser having a capacity for accomplishing the entire condensing requirement of the refrigeration system, and means for selectively connecting said first condenser in series relationship in the refrigeration system with the outlet of said first condenser connected to the inlet of said second condenser.

16. A condenser arrangement for a refrigeration system, comprising a plurality of condenser coils connected

to the refrigeration system in parallel relationship, all but one of said condenser coils having valve means with control means for closing and opening each such condenser coil in response to condenser head pressure respectively dropping or raising from the desired level, and the other said one condenser coil having a pressure responsive valve on the outlet thereof for causing pressure controlled flooding of said coil when the condenser head pressure drops below the desired level.
